(57) **CLAIM**

The ornamental design for a electric light adapter, as shown and described.

DESCRIPTION

FIG. 1 is a top perspective view of the electric light adapter design according to the invention;

FIG. 2 is a front view of the design;

FIG. 3 is a back view of the design;

FIG. 4 is a right side view of the design;

FIG. 5 is a left side view of the design;

FIG. 6 is a top view of the design; and,

FIG. 7 is a bottom view of the design.

The broken line portion of the figure drawings is included to show unclaimed subject matter only and forms no part of the claimed design.

1 Claim, 4 Drawing Sheets

FIG. 1

FIG. 2**FIG. 3**

FIG. 4**FIG. 5**

FIG. 6

FIG. 7
